UNITED STATES PATENT OFFICE.

FRANK VAN CAUWENBERGH, OF ROCKFORD, ILLINOIS.

ROTARY PUMP.

1,172,505.

Specification of Letters Patent. Patented Feb. 22, 1916.

Application filed March 5, 1915. Serial No. 12,314.

To all whom it may concern:

Be it known that I, FRANK VAN CAUWENBERGH, a citizen of the United States, residing at Rockford, in the county of Winnebago and State of Illinois, have invented 5 certain new and useful Improvements in Rotary Pumps, of which the following is a specification.

This invention relates in general to rotary pumps adapted to pump liquid and has 10 more particular reference to those used for pumping and circulating oil in systems for supplying a continuous stream of oil to cutting tools in metal-working machines.

15 In the operation of metal-working machines such as lathes, milling machines, drills, grinders, power saws and various other machines, it is desirable and moreover, essential in many instances, to supply 20 a continuous stream of oil to the cutting tool during operation in order to produce proper cutting and to maintain the tool in cutting condition. The used oil drains into a tank and is again pumped through pipes 25 to the cutting tool, and thus kept circulating, as is well understood in machine shop practice. Much difficulty has been experienced in attempting to provide a pump that will operate in these systems without 30 becoming worn and clogged in a short time, due to the fine metal filings and chips in the oil which can not be practically separated therefrom by sieves.

The primary object of my invention is 35 to provide an improved rotary pump particularly adapted for use in oil-circulating systems, such as those above described and which will operate very efficiently without becoming clogged and worn as do rotary 40 pumps in general use.

Another object of my invention is to provide a rotary pump of improved design and few parts whereby the pump may be manufactured at a low cost.

45 Other objects of my invention and attendant advantages thereof will be readily apparent as the same becomes better understood by reference to the following detail description when considered in connection 50 with the accompanying drawings; wherein,

Figure 1 is a plan view of a rotary pump embodying my improvements; Fig. 2 is a vertical sectional view through the pump taken on the line 2-2 of Fig. 3; Fig. 3 is

a vertical transverse sectional view through 55 the pump taken on the line 3-3 of Fig. 2; Fig. 4 is a plan section taken on the line 4-4 of Fig. 2, and Fig. 5 is a detail in perspective of the rocking abutment.

Referring to the drawings, it will be observed that the working parts or elements are contained in a substantially circular chamber designated by reference character 4 formed by a casing or housing comprising a main body 5 open at one side and a 60 plate 6 covering the said open side and fastened to the said body by machine screws 7. A shaft 8, passing through and journaled in the plate 6 and in the body 5 wall opposite said plate, has fixedly mounted thereon within the chamber a rotor or piston designated generally by reference character 9. This rotor is shaped to provide three equally spaced, radially extending 65 pistons 11, which collectively are of a 70 general triangular shape. A portion 12 of the wall of the body 5 is formed on an arc concentric with the pivot axis of the rotor and in such proximity to the rotor as to form a stationary abutment with which the 75 ends of the pistons co-operate during operation. The rotor extends crosswise of the chamber the entire width thereof, so that passage of liquid through the portion of the chamber occupied by the rotor is precluded, although such passage is permitted 80 by rotary movement of the rotor in a clockwise direction, viewing Fig. 2, whereby liquid will be drawn by the pistons from the intake 15 at the base of the chamber 90 and raised between the rotor and the stationary abutment 12. A suitable stuffing-box 13 is provided for the shaft bearing in the plate 6. The shaft 8 may be driven 85 by any suitable means, as for instance by a pulley 14 as shown in the drawings.

A rocking abutment designated generally by reference character 16, disposed within the chamber 4 and shaped to provide a pair of spaced arms 17 in engagement with the periphery of the rotor on diametrically opposite sides thereof, is pivotally mounted on a pin 18 carried by the casing 5 and plate 6, whereby the abutment will be oscillated 100 as the rotor is turned. The periphery of 105 the rotor or of the piston arms thereof is so shaped that the diametrical distance through the rotor at any radial point is

constant, and thus the abutment arms will be maintained in engagement with the periphery of the rotor as the same is turned. The upper arm of the abutment and the pivoted portion thereof are of the same width as the rotor, as is seen in Figs. 3 and 5, the lower arm being of less width, as is also shown in said figures. The pivoted end of the abutment is curved as at 19 to form a tight joint with a similarly curved recess in the adjacent wall of the body 5. It is obvious that the chamber 4 is divided by the rotor and rocking abutment which coöperate with opposite walls of the body 5 in a manner to preclude, when the rotor and abutment are stationary, passage of liquid through the chamber to opposite sides of the rotor and abutment, and that with an exhaust opening leading from the chamber at any point above said division thereof, the liquid may be drawn from the inlet 15 by turning the rotor and raised by the pistons above said division of the chamber and expelled through the said exhaust opening.

Since, as above explained, I have provided a pump especially adapted for pumping oil laden with minute steel or iron filings and chips because of conditions under which oil is used, it is obvious that there will be a tendency for many of these small particles to settle and lodge in the pump and clog the working parts thereof. My improvements have been designed to obviate this difficulty and, while providing simplified pumping elements, I have so arranged them and the course of liquid passage through the pump that the tendency for said particles to become lodged in the pump is reduced to a minimum. It will be seen that since the lower arm of the abutment member is of less width than the chamber and the inlet is located at the bottom thereof, any settling particles will be immediately drawn by the pistons into circulation. Since the lowest point in the chamber above the rotor and rocking abutment is adjacent to the pivot of the latter, I have located the exhaust opening 21 at this point and have formed the abutment with a channel 22, as best shown in Fig. 3, leading downwardly to the exhaust opening, thereby providing in an efficient manner against the possibility of particles settling and becoming lodged in the upper portion of the chamber so as to clog the working parts.

It is believed that for the foregoing, my invention and its mode of operation will be readily understood, and that the details of structure and relative arrangement as herein shown might be variously modified without involving any substantial change in structure or its principles of operation. It should, therefore, be understood that I do not limit myself to the exact construction herein shown and described, but reserve

the right to make such variations therein as fall within the spirit and scope of the invention as expressed in the appended claims.

I claim:

1. In a rotary pump, the combination of a rotary piston having three radially extending and equally spaced piston-arms, a stationary abutment with which said arms coöperate as the piston is rotated, and a rocking abutment engaging the periphery of the piston on diametrically opposite sides thereof, the periphery of the piston being shaped to maintain said rocking abutment in said engagement as the piston is rotated.

2. A rotary pump comprising a chamber having an intake and an exhaust opening spaced apart, a piston mounted to rotate in the chamber and having a plurality of integrally constructed piston arms adapted to coöperate with a portion of the chamber wall intermediate said intake and exhaust openings, a rocking abutment engaging the periphery of the piston and being arranged to preclude passage of liquid in the chamber between the said intake and exhaust openings, and means connected to and movable with said abutment and engaging the periphery of the piston for positively holding said abutment in engagement with the periphery of the piston continuously during complete rotation thereof.

3. In a rotary pump, the combination of a chamber having an intake and an exhaust opening spaced apart, a triangularly shaped piston mounted to rotate in the chamber so that the vertices thereof constituting pistons are adapted to engage a portion of the wall of the chamber intermediate the intake and exhaust openings, and an abutment pivotally mounted in the chamber at the side thereof opposite said wall-engaged portion and shaped to engage the periphery of the piston at diametrically opposite sides thereof, whereby to be maintained in engagement with the periphery of the piston as the same is rotated and to preclude passage of liquid from the exhaust to the intake opening through the abutment side of the chamber.

4. In a rotary pump, the combination of a piston chamber, a piston rotatably mounted therein and having a plurality of integrally constructed, radially extending piston arms adapted to coöperate with one side of the piston chamber as the piston is rotated, a rocking abutment pivotally mounted in the piston chamber and having a pair of integrally constructed arms spaced apart and engaging the peripheral face of the piston on diametrically opposite sides thereof, the periphery of the piston being so shaped that the abutment arms will engage the same at all times during rotation thereof, whereby to preclude passage of liquid from one to the other side of the piston at the abutment side thereof, and the casing being provided

with an intake opening on one side of the piston and abutment and with an exhaust opening on the other side thereof.

5. A rotary pump comprising a casing forming a piston chamber, a piston rotatably mounted therein and having a plurality of rigid, radially extending arms, a stationary arcuate abutment with which said arms coöperate, a rocking abutment engaging the periphery of the piston on diametrically opposite sides thereof and being pivotally mounted and arranged in the chamber to preclude passage of liquid past the rocking abutment, the periphery of the 15 piston being so shaped that said rocking abutment will be maintained in engagement therewith on diametrically opposite sides thereof, and the casing being provided with an intake and an exhaust opening to said 20 chamber at opposite sides of the division in the chamber formed by the piston and the stationary and rocking abutments.

6. In a rotary pump, the combination of a casing forming a piston chamber, a piston mounted therein to rotate on a horizontal 25

axis and having a plurality of rigid piston arms, the casing being shaped to provide a stationary abutment at one side of the piston with which the arms thereof coöperate, a rocking abutment pivotally mounted in the 30 chamber on a horizontal axis in substantially horizontal alinement with the said piston axis and having a pair of oppositely extending arms engaging the periphery of the piston at diametrically opposite sides thereof, 35 whereby the piston and rocking abutment divides the chamber horizontally, the lower arm of the rocking abutment being of less width than the chamber, and the casing having an intake opening into the lower 40 portion of the piston chamber and an exhaust opening from the chamber above the said division thereof formed by the piston and rocking abutment and adjacent to the pivoted portion of the said rocking abut- 45 ment.
